G. REMNSNIDER,
FEED CARRIAGE FOR STENCIL MACHINES.
APPLICATION FILED MAY 24, 1920.

Patented Apr. 12, 1921.

UNITED STATES PATENT OFFICE.

GEORGE REMNSNIDER, OF BELLEVILLE, ILLINOIS.

FEED-CARRIAGE FOR STENCIL-MACHINES.

1,374,234.

Specification of Letters Patent.

Patented Apr. 12, 1921.

Application filed May 24, 1920. Serial No. 383,628.

To all whom it may concern:

Be it known that I, GEORGE REMNSNIDER, a citizen of the United States of America, residing at Belleville, county of St. Clair, 5 State of Illinois, have invented a certain new and useful Feed-Carriage for Stencil-Machines, of which the following is such a full, clear, and exact description as will enable any one skilled in the art to which it 10 appertains to make and use the same, reference being had to the accompanying drawings, forming part of this specification.

My invention relates to a feed carriage for stencil machines and is particularly adapted 15 for use in connection with machines of the general type shown and described in my Patent No. 1,131,956 of March 16, 1915. It may, however, be used with various other types of stencil cutting machines.

20 The object of my invention is to produce a simple and compact device of the class described which will be reliable in operation and which will firmly grip the stencil sheet so as to prevent the possibility of the sheet 25 slipping during the operation of the device.

In the accompanying drawings which 30 illustrate one form of device made in accordance with my invention, Figure 1 a top plan view, Fig. 2 a front elevation, Fig. 3 a section taken on line 3—3 of Fig. 4. Fig. 4 is an enlarged front view of a portion of the device, some of the parts being broken away. Fig. 5 is an enlarged section taken on the line 5—5 of Fig. 1. Fig. 6 is a section taken on the line 6—6 Fig. 4, and Fig. 35 7 is a section taken on the line 7—7 of Fig. 4.

10 indicates the stencil supporting plate of a stencil machine. Upon the forwarding 40 edge of the plate 10 rests the horizontal flange of an angle plate 11. Said plate 10 is preferably offset at 12 so as to bring the upper face of the horizontal flange of the angle plate flush with the upper face of the 45 body of the plate 10. The front edge of plate 10 is provided with a turned over portion 13 forming a downwardly projecting flange which rests in a guide way formed between the vertical flange of the plate 11 50 and a rack bar 14 which is secured to said plate by means hereinafter to be pointed out. Secured to the lower part of the plate 10 is a guide bar 15 forming a guide for the back and lower edge of the rack bar 14. This 55 guide bar 15 is provided with a removable front plate 16 over-lapping the front face

of the rack bar 14. The rack bar is actuated by means of a gear wheel 17 operated by any suitable mechanism which is not illustrated, as it forms no part of the present invention. 60

20 are clamping fingers each of which is provided with a recess 21 preferably in the form of circular apertures. These recesses 21 are adapted to co-operate with conical bosses 22 formed in the horizontal flange of 65 the angle plate 11 to clamp the stencil sheet so as to effectively prevent its slipping during the operation of its device; a portion of the material of the stencil sheet being forced into the recesses 21 by the bosses 22. Each 70 of the fingers 20 is provided with a lateral projection 23 bearing on one end a compression spring 24, the opposite end of which bears against a member 25 forming a combined stop block and fastening pin. Resting 75 on the upper faces of the blocks 25 is an actuating bar 26 provided with slots 27 to receive pivot pins 28 which also serve to secure the parts of the device together. The bar 26 is also provided on its rear face with 80 projections 29 adapted to come into contact with the curved end of fingers 20 and thus raise fingers out of contact with the horizontal flange of plate 11 when the bar 26 is moved toward the left hand end of the 85 carriage. This movement of the bar 26 is secured by means of lever 30 pivoted on one of the pins 28 preferably adjacent to the center of the carriage and provided with a cam slot 31 engaging with a cam 32 carried on the rear face of the bar 26.

33 is a channel plate forming a housing for inclosing the bar 26 and springs 24. This channel bar is secured in position by means of the member 25 and pivot pins 28 95 which parts extend through the said bar 33, the vertical flange of the plate 11 and the rack bar 26 as shown in Figs. 6 and 7.

The operation of my device is as follows:

When it is desired to insert a stencil sheet 100 in the machine the lever 30 is moved toward the right thus causing the bar 26 to move toward the left so that the projections 29 will engage with the curved ends of the fingers 20 and cause all of said fingers to move 105 simultaneously on their pivoted springs 23 against the tension of the pins 24. The sheet is now inserted between the fingers 20 and the horizontal flange of plate 11, the vertical portions of the fingers forming a stop for 110 the front edge of the sheet. The lever 30 is now again moved into the position shown

in Fig. 4 positively moving the bar 26 toward the right hand end of the machine and allowing the springs 24 to operate on the clamping fingers. This causes the bosses 5 22 to force portions of the stencil sheet into the recesses 21 thus effectively clamping the sheet so that it cannot slip during operation of the machines.

Having fully described my invention, 10 what I claim as new and desire to secure by Letters-Patent of the United States is:

1. In a device of the class described, the combination with a stencil supporting member, of a feed carriage movable relative thereto, a stencil gripping finger mounted on said carriage and provided with a recess, and a boss on said stencil supporting member for forcing the stencil into said recess. 15
2. In a device of the class described, the combination with a stencil supporting member, of a feed carriage movable relative thereto, a stencil gripping finger mounted on said carriage and provided with a recess, and an obtuse conical boss on said stencil 20 supporting member for forcing the stencil sheet into said recess.
25

3. In a device of the class described, the combination with a stencil supporting member, of a feed carriage movable relative thereto, a plurality of stencil gripping fingers mounted on said carriage and each provided with a recess, bosses for forcing the stencil sheet into the said recesses, and means for simultaneously actuating said fingers to release the stencil sheet. 30
35

4. In a device of the class described, the combination with a stencil supporting member, of a feed carriage movable relative thereto, a plurality of stencil gripping fingers pivotally mounted on said carriage, springs for independently actuating said fingers to grip the stencil sheet, and means for simultaneously actuating said fingers to release the stencil sheet. 40
45

5. In a device of the class described, the combination with a stencil supporting member, of a feed carriage movable relative thereto, a plurality of stencil gripping fingers mounted on said carriage, springs for 50 actuating said fingers to the stencil sheet, a longitudinally movable bar for simulta-

neously actuating said fingers to release the stencil sheet, and a channel bar inclosing said springs and actuating bar.

6. In a device of the class described, the combination with a stencil supporting member, of a feed carriage movable relative thereto, a plurality of stencil gripping fingers pivotally mounted on said carriage, springs for actuating said fingers to grip 60 the stencil sheet, a longitudinally movable bar for simultaneously actuating said fingers to release the stencil sheet, and a channel bar inclosing said springs and finger actuating bar. 65

7. In a device of the class described, the combination with a stencil supporting plate, of an angle plate movable relative thereto, a feed rack carried by said angle plate, a plurality of stencil gripping fingers carried 70 by said angle plate, a finger release bar carried by said angle plate but movable relatively thereto, a channel bar inclosing said release bar, and means for actuating said release bar. 75

8. In a device of the class described, the combination with a stencil supporting plate, of an angle plate movable relatively thereto, a feed rack carried by said angle plate, a plurality of stencil gripping fingers pivoted 80 to said angle plate, springs for actuating said fingers to grip the stencil sheet, a finger release bar carried by said angle plate but movable relatively thereto, a channel bar housing said release bar, and means for 85 actuating said release bar.

9. In a device of the class described, the combination with a stencil supporting plate provided with a flange, of an angle plate movable relatively thereto, a feed rack carried by said angle plate and forming therewith a guide channel for said flange, a plurality of stencil gripping fingers pivoted to 90 said angle plate, springs for actuating said fingers to the stencil sheet, a finger release bar, a channel bar inclosing said spring and release bar, and means for actuating said release bar. 95

In testimony whereof, I have hereunto set my hand and affixed my seal.

GEORGE REMNSNIDER. [L. s.]
